Primary Examiner — Ruth McInroy(74) *Attorney, Agent, or Firm* — Studebaker & Brackett PC(57) **CLAIM**

The ornamental design for a suction head for a vacuum cleaner, as shown and described.

DESCRIPTION

FIG. 1 is a front, top and right-side perspective view of a suction head for a vacuum cleaner showing my new design; FIG. 2 is a front view thereof;

FIG. 3 is a rear view thereof;

FIG. 4 is a top view thereof;

FIG. 5 is a bottom view thereof;

FIG. 6 is a right-side view thereof; and,

FIG. 7 is a left-side view thereof.

The broken lines shown represent unclaimed subject matter of the suction head for a vacuum cleaner and form no part of the claimed design.
